[57] CLAIM

The ornamental design for a portable folding toilet seat, as shown and described.

DESCRIPTION

FIG. 1 is a top plan view of a portable folding toilet seat showing our new design;

FIG. 2 is a bottom plan view thereof;

FIG. 3 is a side elevational view thereof, the opposite side being a mirror image of the side shown;

FIG. 4 is a rear elevational view thereof;

FIG. 5 is a top plan view showing the seat in a folded position, the bottom being a mirror image of the top shown;

FIG. 6 is a left side elevational view of FIG. 5;

FIG. 7 is a right side elevational view of FIG. 5; and

FIG. 8 is a rear elevational view of FIG. 5.
